BUILDING CONSTRUCTION

Andrew Hohner, Ottawa, Ill.

Application June 12, 1936, Serial No. 84,907

8 Claims. (Cl. 72—19)

This invention relates to building construction.

It is an object of this invention to provide an improved building construction which is relatively simple and inexpensive in construction and efficient in use.

Another object of the present invention is to provide a novel construction for applying a brick veneer surface or facing to the wall of a building.

Other objects of the invention are: to provide a new and improved brick and a new and improved device for mounting the same upon the wall of a building; and to provide a novel corner brick and a novel device for holding the same in position of use.

I am aware of the fact that heretofore various types of building construction have been employed utilizing bricks and various means or devices for attaching the same to the wall of a new building, but, insofar as I am aware, none of these building units has ever been devised for attaching the bricks to the wall of an old building having wooden siding thereon. Accordingly, it is another object of the present invention to provide a new and improved building unit embodying a novel means for attaching the bricks embodied therein to the siding of an old building in such a manner as to provide the latter with a brick veneer or facing.

I am also aware of the fact that various building units have heretofore been employed in which there have been embodied bricks and various devices for attaching the same to the wall of a building. Many of these building units have, however, embodied bricks, and various attaching means or devices therefor, of such a complicated design and form or construction that they are expensive to manufacture and assemble, from the standpoint of material, time, and labor involved. Thus some of these prior art building units have embodied attaching means or devices for the bricks consisting of heavy, thick, wood strips which are expensive both from the standpoint of time and labor involved in manufacture and material required, and others have embodied metal attaching devices of special and complicated design, requiring special tools and operations to form the same, thereby making them costly from the standpoint of time, labor and material required.

Another object of the present invention, therefore, is to provide a new and improved building unit embodying a brick, and attaching or supporting means therefor, which are relatively simple in design and inexpensive to manufacture and assemble, from the standpoint of the material, time, and labor involved.

Other objects will appear hereinafter.

The invention consists in the novel combination and arrangement of parts to be hereinafter described and claimed.

The invention will be best understood by reference to the accompanying drawings showing the preferred form of construction, and in which:

Fig. 1 is a perspective view showing a preferred form of the new building unit as applied to the sides and corner of a new building;

Fig. 2 is a perspective view showing a preferred form of the brick embodied in the new building unit;

Fig. 3 is a vertical sectional view showing the new building unit attached to the wall of a new building;

Fig. 4 is a perspective view showing a preferred form of the corner brick embodied in the new building unit;

Fig. 5 is a horizontal sectional view showing a preferred form of the corner construction embodied in the new building unit; and

Fig. 6 is a perspective view, partly in section, showing a modified form of the invention which is designed to be applied to the wall of an old building having wooden siding thereon.

A preferred form of the invention is shown in Figs. 1 to 5 inclusive of the drawings, and is therein shown as applied to the wall of a new building, the new building unit or construction embodied in this form of the invention being generally indicated at 10 and comprising a brick or tile 11 which may be made of any suitable material and by any desired and suitable method.

The new brick 11 comprises a body 12 and this body 12 is provided on its upper surface 13 with a horizontally and axially extending groove 14; and on its lower or bottom surface 15 the brick 10 is provided with a horizontally and axially extending groove 16. The outer or front surface 17 of the brick 11 is substantially flat and on its inner or rear surface the brick 11 is provided with a horizontally and axially extending groove 18 which provides a dead air space for heat insulation when the brick 11 is in use and attached to sheathing or wall 19 (Fig. 3). Formed in the brick 11, and continuous with, and as a part of, the groove 18, is an undercut portion or groove 20, and extending downwardly over, that is, overhanging, this undercut portion or groove 20 is a flange 21, the inner surface or edge 22 of this flange 21 being relatively straight (Fig. 2) but inclined from both the horizontal and the vertical.

The new building unit 10 likewise includes a means or device for attaching the bricks 11 to the

wall or sheathing 19 of a building, and for supporting the same thereon, and this means or device includes an attaching member in the form of a relatively thin metal strip 23 which is attached to the wall 19 by suitable fastening elements in the form of nails 24 or the like. Each of these attaching strips 23 includes a flat straight lower portion 25, which is attached to the wall 19 by means of the fastening elements 24, and each of these attaching strips 23 also includes an outwardly and upwardly angled portion or flange 26.

The new building unit 10 also includes a corner construction, which is generally indicated at 27, and this corner construction includes a corner brick 28 (Fig. 4) which is substantially rectangular in cross section, although it may be made in other forms, as will be explained hereinafter. The corner brick 28 includes a relatively long arm 29 and a relatively short arm 30, and the long arm 29 is provided, on its inner surface, with a vertically extending groove or channel 31 which forms a dead air insulation space 31 when the brick is attached to the wall or sheathing 32 of a building. The outer marginal edge of the groove or channel 31 is defined by an undercut portion or groove 33 and extending over this undercut portion or groove 33 is a flange 34. Similarly, the inner marginal edge of the groove 31 is formed by an undercut portion 35 and the outer marginal edge of the groove 31 is formed by an undercut portion 35 and extending over this undercut portion 35 is a flange 36 which has a straight-sided inner surface or edge 59 (Figs. 4 and 5).

In a similar manner, the inner surface of the short arm 30 of the corner brick 28 is provided with a groove or channel 37 which, when the said brick is in use, forms a dead air insulation space 37, the outer marginal edge of this groove 37 being formed by an undercut portion or groove 38 over which a flange 39 extends, and this flange 60 has a straight-sided inner edge or surface 60. The corner construction unit 27 includes a means or device for attaching the corner bricks 28 to the sheathing or wall 32 of a building (Fig. 5) and this means or device consists of three similar and vertically extending thin metal strips 40, 41, and 42 which are attached to the wall or sheathing 29 by means of fastening elements such as nails or the like.

The attaching strips 40, 41 and 42 are relatively short, that is, when in position of use they extend vertically only the vertical length or height of the corner bricks 28. The attaching strip 40 includes a relatively straight flat portion 43 which is attached to the wall or sheathing 32 by means of fastening element, such as nails or the like, and this strip 40 also includes an outwardly angled portion or flange 44. Similarly, the strip 41 includes a relatively flat, straight portion 45 which is attached to the sheathing or wall 32 by means of suitable fastening elements, such as nails, and the strip 41 also includes an outwardly angled portion or flange 46. The attaching strip 42 is similar to the attaching strips 40 and 41 and includes a relatively flat, straight portion 47 which is attached to the wall or sheathing 32 by means of nails or the like, and this strip 42 also includes an outwardly angled portion or flange 48.

In the practice and use of the form of the present invention which is shown in Figs. 1 to 5 inclusive, the horizontally extending attaching and supporting strips 23 are attached to the wall or sheathing 19 of a new building, by means of fas-

tening elements such as nails or the like, and the bricks 11 are then placed on, or inserted onto, the attaching and supporting strips 23 in such a manner that the upwardly and outwardly flared portions or flanges 26 of the strips 23 project into the undercut portions or grooves 20 which are formed in the bricks 11, and the inclined surfaces or inner edges 22 of the bricks 11 lie against and bear upon the upper and rear surfaces of the flanges 26; the attaching and supporting strips 23 thus holding and supporting the bricks 11 on the wall or sheathing 19. As each row of the bricks 11 is laid, the grooves 14 in the next adjacent lower row of bricks are filled with mortar, and when the bricks in the next adjacent higher row are pressed down onto the bricks 11 therebelow the mortar enters and fills the grooves 16, thus forming a lock joint 49 (Fig. 3) between the bricks and thereby holding the same in position of use upon the wall or sheathing 32 and against displacement therefrom.

When the new building unit 10 is in use the grooves 18 in the bricks 11 cooperate with the wall or sheathing 19 to form dead air insulation spaced for preventing the passage or transfer of heat therethrough, thus providing an efficient heat insulation. It is likewise to be noted that the new building unit is relatively simpler in construction and less expensive to manufacture and assemble, from the standpoint of time, labor, and material involved, than some of the prior art building units of an analogous or similar nature, since in the present building unit the bricks 11 are very simple in design and the attaching and supporting strips 23 are likewise very simple in design and inexpensive to manufacture and install since they are merely a flat strip of metal, such, for example, as galvanized iron, bent to form the upwardly and outwardly flared flange 26; it being noted, in this connection, that this operation may be accomplished without the use of, or necessity for, any special forming tools or dies such as are required in the manufacture of the attaching and supporting strips which are embodied in certain of the prior art building units of an analogous nature. Moreover, the attaching strips 23 are economical from the standpoint of material used since they may be made from relatively thin flat stock or strips of metal and they have this advantage over certain of the prior art building units which employ relatively thick heavy metal or thick wood strips for supporting the bricks in place and which strips are expensive to manufacture and install, from the standpoint of material, time, and labor involved.

The manner of assembling the corner construction 27 is illustrated in Fig. 1 wherein it will be seen that the arrangement of the bricks 28 in alternate rows of bricks are reversed, that is, the short arm 30 of one brick is laid over the long arm 29 of the next adjacent brick therebelow. In assembling these corner units 27 the short attaching and supporting strips 40, 41 and 42 are attached to the wall or sheathing 29 by means of fastening elements such as nails or the like, whereupon the corner bricks 28 are arranged above, and then slid down onto, the attaching strips 40, 41 and 42, thereby entering the angled portions or flanges 44, 46 and 48 thereof in the undercut portions or grooves 33, 35 and 38 respectively, thereof, and under the corresponding flanges 34, 36, and 39, respectively; thereby holding the corner bricks 28 in position of use, and against lateral displacement therefrom, without the use of any mortar, although if desired, the

top and bottom surfaces of the corner bricks 28 may be provided with grooves, such as the grooves 14 and 16 in the bricks 11 so that they may, if desired, be interlocked by means of 5 mortar lock joints such as the lock joint 49.

While the corner bricks 28 have been shown as embodying the three flanges or ribs 34-36-39 and corresponding undercuts or grooves 33-35-38, respectively, the middle flange or rib 36 and 10 the corresponding undercut or groove 35, and attaching and supporting strip 11, may be dispensed with, if desired, since the two attaching strips 40 and 42 and the corresponding undercuts or grooves 33-38 and flanges or ribs 34-39, 15 are sufficient to hold the corner bricks 28 in position of use and against lateral displacement therefrom.

A modified form of the present invention is shown in Fig. 6, and this form of the invention is 20 especially adapted for use in conjunction with, or application to, old buildings which have wooden siding. Accordingly, this modified form of building unit, which is generally indicated at 50, is shown as applied to the wooden siding 51 of an old building, the siding 51 being attached to the inner wall or sheathing 52.

In the use of the modified form of building unit which is shown in Fig. 6, the bricks 11 (Fig. 2) are also employed and are locked together in 30 the manner illustrated in Fig. 3, that is, by the mortar or lock joint 49. This modified form of the invention, illustrated in Fig. 6, differs from the form of the invention which is shown in Figs. 1 to 5, inclusive, in that it is especially adapted 35 for use upon old wooden buildings which are provided with wooden siding 51; and the specific difference between the form of the invention shown in Figs. 1 to 5, inclusive, and the form of the invention which is shown in Fig. 6, resides in 40 the manner of mounting the anchoring and supporting strips 53 upon the siding 51, this being accomplished as follows: At the start of the operation a series of parallel, vertically extending grooves or channels 54 are formed in the siding 51, by means of an electric rotary saw, or by any other suitable tool, these grooves 54 extending only partially through the thickness of the siding 51. Relatively thin wood strips 55 are then inserted into the grooves or channels 54, 45 wherein they are fastened to the siding 51 by any suitable fastening means such, for example, as nails. The attaching and supporting strips 53 are then secured, horizontally, to the vertical strips 55 by means of suitable fastening elements, 50 such as the nails 56. These attaching and supporting strips 53 are preferably made of thin metal so that the nails 56 may be readily driven therethrough; it being noted, in this connection, that these attaching and supporting strips 53 are 55 exactly similar in construction and design to the strips 23. Thus, each of the strips 53 includes a relatively straight, lower portion or base 57, through which the nails 56 are driven, and each strip 56 also includes an upwardly and outwardly 60 flared portion or flange 58 on which the bricks 11 are suspended to complete the operation, the bricks 11 being arranged upon the strips 53 and locked together in the manner illustrated in Fig. 3, and hereinbefore described in connection with 65 the form of the invention shown in Figs. 1 to 5, inclusive.

The form of the invention illustrated in Fig. 6 provides a new and inexpensive method and construction for putting a brick facing or veneer 70 upon an old building which is provided with

wooden siding, and this is simple and inexpensive from the standpoint of time, labor and material required.

If desired, the corner construction 27, including the bricks 28, may be employed in connection 5 with the form of the invention shown in Fig. 6, although this is not absolutely essential since other forms of corner construction, than that shown, may be used in connection with this form of the invention, if desired and the modified form 10 of the invention shown in Fig. 6 is not limited to use with the corner construction or unit 27.

The particular angle at which the upwardly flared flanges 26 and 58, extend from the straight flat portions of the attaching strips 23 and 53, 15 respectively, may be varied within a wide range between the horizontal and vertical, that is, through an arc of somewhat less than 90°, and this angle need not be confined to the particular angle shown in the drawings.

It is also to be noted that while the corner bricks 28 which are shown in the drawings are made substantially L-shaped and with their arms 29 and 30 intersecting at an angle of ninety degrees (90°), this angle may be varied, if desired, 25 so as to accommodate the bricks 28 to the various angles found in the corners of bay windows, and other places, where the angles may be either more or less than ninety degrees, (90°).

The metal attaching and supporting strips 23 30 and 53 may be placed on the walls of buildings in such manner as to allow a full size brick above and below all openings between the siding or sheathing as well as at the tops of porch columns and these metal strips 23 and 53 may be spaced 35 to allow for either a light or heavy mortar joint, as desired.

It is also to be noted that while the new construction is shown as applied to the outside wall 40 of a building the same may, if desired, be used to provide a plain or glazed surface or facing on the interior walls of a building and, in this event, the position or angle of the arm 30 of the corner brick 27 will be reversed so that it will extend downwardly, as seen in Fig. 5, rather than upwardly, as shown, and in this event the flange 39 on the arm 30 will be arranged on the outer side of the same, rather than on the inner side of the same, as shown.

While I have illustrated and described the preferred form of construction for carrying my invention into effect, this is capable of variation and modification, without departing from the spirit of the invention. I, therefore, do not wish to be limited to the precise details of construction set forth, but desire to avail myself of such variations and modifications as come within the scope of the appended claims.

Having thus described my invention, what I claim as new and desire to protect by Letters 60 Patent is:

1. A building wall comprising sheathing, bricks, each of said bricks having a channel-shaped groove formed therein on its inner surface and provided with a flange projecting over a portion 65 of said groove, said grooves providing dead air insulation spaces when the said brick is in use, and means for attaching the said bricks to the said sheathing, said means consisting of a thin strip of flat metal stock having a flat straight 70 portion attached to the said sheathing, by means of nails or the like, and said strip including an outwardly flared portion providing a flange projecting into the said groove and under the said first-named flange for supporting the said brick 75

in position of use upon the wall or sheathing of a building.

2. A building wall comprising sheathing, bricks, each of said bricks having a channel-shaped groove formed therein on its inner surface and provided with a flange projecting over a portion of said groove, said grooves providing dead air insulation spaces when the said bricks are in use, said flange having a straight sided inner edge 10 inclined at an angle relative to the position of the said bricks when the latter are in use, and means for attaching the said bricks to the said sheathing, said means consisting of a thin strip of flat metal stock having a flat straight portion attached to the said sheathing by means of nails or the like, and said strip including an outwardly flared portion providing a flange projecting into the said portion of said groove, and under the said first-named flange in a position wherein the 20 said edge of the latter bears against the said second-named flange, so as to support the said bricks in position of use upon the said sheathing.

3. A building wall comprising sheathing, bricks, each of said bricks having a channel-shaped groove formed therein on its inner surface providing a dead air insulation space when the bricks are in use, said groove including an undercut end portion and having a flange projecting over said groove, and means for attaching the 30 said bricks to the said sheathing, said means consisting of a thin strip of flat metal stock having a flat straight portion attached to the said sheathing by means of nails or the like, and said strip including an outwardly flared portion providing a flange projecting into the said undercut portion of said groove and under the said first-named flange for supporting the said bricks in position of use upon the said sheathing.

4. A building wall comprising sheathing, bricks, each of said bricks having a relatively wide and horizontally extending channel-shaped groove formed on its inner side providing a dead air insulation space when the brick is in use, said groove including an upper end and undercut 40 portion and having a flange overhanging said undercut portion and provided with a straight inner edge inclined at an angle between the vertical and the horizontal when the brick is in upright or position of use, each of said bricks having a groove formed therein on its upper 45 surface and also having a groove formed therein on its bottom surface for the reception of mortar so as to form a lock joint with the corresponding bricks above and below the same, and means 50 for attaching the said bricks to the said sheathing, said means consisting of a thin strip of flat metal stock having a flat straight lower portion attached, in horizontal position, to the said sheathing by means of nails or the like, said strip including an upwardly and outwardly flared 55 portion providing a flange projecting into the said upper end portion of said groove and under the said first-named flange, and in a position wherein the said edge bears against the said second-named flange, so as to support the said bricks in position of use upon the said sheathing.

5. A corner brick construction for buildings, comprising a brick including two intersecting arms adapted to embrace or lie against corresponding walls of a building at a corner of the 70 same, each of said arms having a relatively wide and vertically extending channel-shaped groove formed therein on its inner surface providing a dead air insulation space when the said brick is in use, each of said grooves having an undercut

portion adjacent the laterally outer end thereof providing an overhanging flange on the corresponding arm of the said brick, and means for attaching the said brick to the wall or sheathing of a building, said attaching means consisting of 5 relatively thin metal strips each having a substantially flat straight portion adapted to be attached, in vertical position, to the wall of a building, by means of nails or the like, and each of said strips including a portion extending angularly from the said first-named portion of the same and providing a flange receivable in the undercut portion of the corresponding one of the said grooves so as to retain the said brick in position of use upon a wall or sheathing of a building 10 and against horizontal displacement thereon.

6. A corner brick construction for buildings, comprising a brick including two intersecting arms adapted to embrace corresponding walls of a building at a corner of the same, each of said arms having a relatively wide and vertically extending channel-shaped groove formed therein providing a dead air insulation space when the said brick is in use, each of said grooves having an undercut portion adjacent the laterally outer 20 end thereof providing an overhanging flange on the corresponding arm of the brick, one of said grooves having another or second undercut portion adjacent the laterally inner end thereof providing an overhanging flange on the corresponding arm of said brick, and means for attaching the said brick to the wall or sheathing of a building, said attaching means consisting of relatively thin metal strips each having a substantially flat straight portion adapted to be 25 attached, in vertical position, to the wall of a building, by means of nails or the like, and each of said strips including a portion extending angularly from the said first-named portion of the same and providing a flange receivable in the 30 corresponding one of said undercut portions so as to retain the said brick in position of use upon a wall or sheathing of a building and against horizontal displacement thereon.

7. A corner brick construction for buildings, comprising a brick including two arms intersecting at approximately ninety degrees, and each adapted to embrace a corresponding wall of a building at a corner of the same, each of said arms having a relatively wide and vertically extending channel-shaped groove formed therein providing a dead air insulation space when the said brick is in use, each of said grooves having an undercut portion adjacent the laterally outer end thereof providing an overhanging flange on 45 the corresponding arm of the brick, and means for attaching said brick to the wall or sheathing of a building, said attaching means consisting of relatively thin metal strips each having a substantially flat straight portion adapted to be 50 attached, in vertical position, to the wall of a building, by means of nails or the like, and each of said strips including a portion extending angularly from the said first-named portion of the same and providing a flange receivable in the 55 undercut portion of the corresponding one of said grooves so as to retain the said brick in position of use upon a wall or sheathing of a building and against horizontal displacement thereon.

8. A corner brick construction for buildings, comprising a brick including two intersecting arms, one of said arms being longer than the other and each of the same being adapted to embrace a corresponding wall of a building at a 70 75

corner of the same, each of said arms having a relatively wide and vertically extending channel-shaped groove formed therein providing a dead air insulation space when the said brick is in use, 5 each of said grooves having an undercut portion adjacent the laterally outer end thereof providing an overhanging flange on the corresponding arm of the brick, and means for attaching the said brick to the wall or sheathing of a building, 10 said attaching means consisting of relatively thin metal strips each having a substantially flat

straight portion adapted to be attached, in vertical position, to the wall of a building, by means of nails or the like, and each of said strips including a portion extending angularly from the said first-named portion of the same and providing a flange receivable in the undercut portion of the corresponding one of said grooves so as to retain the said brick in position of use upon a wall or sheathing of a building and against horizontal displacement thereon. 5

ANDREW HOHNER. 10
